HIS ATTORNEY.

UNITED STATES PATENT OFFICE.

EDGAR T. MEAKIN, OF BERKELEY, CALIFORNIA.

VALVE STRUCTURE.

Application filed June 12, 1926. Serial No. 115,651.

My invention relates to a vacuum or pressure cooker, and more specifically to a valve structure in the transfer passages for feeding solid matter into and out of the cooker drum. This is a division of my copending application Serial Number 600,593 filed November 13th, 1922 for "Apparatus for processing animal matter."

Before invention of my improved valve device my apparatus for processing animal matter could not be operated continuously, since filling and emptying the cooker drum destroyed the pressure or vacuum within it. This process wasted heat, power, and time, required storing the decomposable animal matter between runs, and caused non-uniform heating of each fresh batch of animal matter fed to the cooker. It is therefore an object of my invention to provide a device for transferring material into or out of a drum without substantial loss of heat or change of pressure in the drum.

It is an object of my invention to provide a gas-tight passage for transferring solids, which is not liable to be clogged by the solids.

It is an object of my invention to provide a gas-tight valve for regulating flow of solids, and which is adapted to exert a great force in closing; and an ancillary object is to provide an improved valve structure having its parts so apportioned that a minimum of stress is caused by this force.

It is an important object of my invention to provide a valve and driving means therefor which are compact, and further, to provide a combination which is simple and rugged in construction.

My invention possesses other objects and features of advantage some of which, with the foregoing, will be set forth in the following description of my invention which is illustrated in the drawings accompanying and forming part of the specification. It is to be understood that I do not limit myself to the showing made by the said description, as I may adopt variant forms of my invention within the scope of the claims.

Referring to the drawings:

Figure 1 is a vertical diametrical section thru my valve structure and thru the driving gear therefor.

Figure 2 is a plan view of the valve structure partly in section as indicated by the line 2-2 in Figure 1.

In terms of broad inclusion the device of my invention includes a valve structure for feeding material into or out of a drum in which the pressure is different from atmospheric, without causing a change of pressure within the drum, and comprises a passage which may be closed by either of two spaced gas-tight valve plates. Each plate is movable, and has an aperture which may be alined with the passage. Means are provided for moving the plates so that the apertures therein aline with the passage at different times, allowing solid matter to pass, without at any time leaving the passage open to break the vacuum or relieve the pressure in the drum with which the passage communicates. Gas-tight packing rings are provided for packing the joints formed by these movable plates and for scraping them clean of matter which adheres to them. The plates are circular, are journaled for rotation relative to the passage, and are provided with ring gears which provide driving means of great strength for the plates. These ring gears are fixed to the peripheries of the plates, and the entire assembly is encased. Driving means are provided for the ring gears, and gas-tight packings are used around the driving shaft as an added precaution against leakage.

In terms of greater detail, the device of my invention comprises a unitary transfer passage 2, 3, 2', 3', and valve housing 4, 4', 6, 6' of cylindrical form; the transfer passage being formed eccentrically thru the housing. Flange faces 7, 7' are formed, on the ends of the housing peripheral to this passage, for connecting it to the chambers between which air-sealed communication is to be established. In this case, I have shown my valve structure arranged between a vacuum or pressure cooker drum inlet 2 and its feed hopper 2'.

The housing is constituted as a coaxial assembly of four circular castings 4, 4', and 6, 6'; the two inner ones 4, 4', of which are provided with eccentric flanged necks 3, 3', which form the major portion of the transfer passage. Bolts 9 thru the flanged portion of the necks secure the two inner castings together, and bolts 11 secure the castings 4, 4' at their periphery between two outer castings 6, 6'.

Means dividing the passage 2, 3, 2', 3', into compartments are provided for closing

the passage. Peripheral shoulders 12, 12' on the outer faces of the inner castings form disk shaped spaces in the housing. Valve plates 14, 14', closely fitted in these spaces, extend across the passage and are adapted to close it. These plates and the spaces in which they work are machined to a close sliding fit, and packing rings 16 housed in annular grooves in the castings immediately surrounding the passage, insure a gas-tight joint for the plates and scrape them clean of any adhering material.

A large aperture having the outline 17 or 17', is formed in each plate, and the plates are journaled for rotation permitting alinement of these apertures with the passage 2, 3, 2', 3', to establish communication between the compartments of the passage. The centers of castings 4, 6, and 4', 6', are expanded axially to accommodate the hubs of the rotary valve plates, and an axial bolt 18 or 18' thru each of these pairs of castings, forms a pin on which the hub is journaled. Each hub is formed of a pair of complementary threaded hub-blocks 19 and 21 or 19' and 21', between which the valve plate is clamped. Holes 22 in the blocks, are adapted to receive a spanner wrench for screwing the blocks together and upon the plate.

Means independent of these hubs and journals are provided for rotating the plates in timed relation such that the openings in the plates will aline with the passage at different times, so that solid matter may be passed, but a barrier always remain to flow of air to the vacuum cooker drum or of steam from a pressure cooker drum. Equal ring gears 23 and 23' are riveted to the periphery of each plate, and a counter-shaft 24 journaled in the housing diametrically opposite to the passage 2, 3, 2', 3', is provided with spur gears 26 and 26' in mesh with the ring gears. A bevel gear 27 fixed to this shaft, is driven by a gear 28 on a drive shaft 29, which may be rotated by any convenient power source. This drive shaft 29 is journaled in a bracket 31 bolted to the side of the housing, while the counter-shaft 24 is journaled in the expanded portions 32 and 32' of the outer castings of the housing. Locked thrust bolts 33 and 33' are threaded axially of the counter-shaft in these expanded portions of the housing, and permits its axial adjustment.

The above described driving means permits use of very thin valve plates, for no driving stress is transmitted thru the hubs or journals to the centers of these plates. Moreover, great driving torque is exerted thru the large ring gears; so that the plates will tend to slice thru any solid matter which blocks their positive closure. The device is rendered compact by the light hub construction and by the elimination of large driving gears at the plate centers.

As a further precaution against leakage

between the passage and atmosphere, packing glands are provided for the counter-shaft by the cup-shaped flanges 34, 34' depending from the inner castings and threaded to receive the packing gland nuts 36, 36'. It is possible, especially because of these packing glands 34, 34', to remove the packing rings 16 from the periphery of the passage to the peripheries of the valve plates, and to allow the fatty materials of the animal matter being processed to work back and lubricate the moving parts. In general however, I prefer the illustrated placement of these packing rings and I therefore provide grease cups 37, 37', 38 and 38', respectively for the two valve plate journals and the two counter-shaft bearings. A grease cup 39 is also provided, for the drive shaft bearing.

The valve structure is assembled with the apertures 17 and 17' in the two valve plates out of vertical alinement and preferably 180° apart. Since the gear ratios are equal, it is evident that only one gate will open to the passage 2, 3, 2', 3', at a time.

In operation, solid matter above the valve structure will pass the upper plate 14' during a portion of its revolution and preferably until the compartment of the passage above the lower plate 14 is full. Continued rotation of the drive shaft closes the upper gate and opens the lower gate to allow discharge of this solid matter, but since the upper gate is then closed, the pressure in the drum with which the passage communicates, remains unchanged.

I claim:

1. In a transfer passage for solids, a pair of spaced gates, means for operating said gates in time with each other so that one gate will remain closed while the other is open, and packing means cooperating with said gates for resisting differences of pressure at opposite ends of the passage.

2. In a transfer passage for solids, a pair of spaced gates, means for operating said gates in time with each other so that one gate will remain closed while the other is open, and packing rings closely surrounding the passage and cooperating with said gates for resisting differences of pressure on opposite sides of each of said gates.

3. In a transfer passage for solids, movable apertured plates for dividing said passage into non-communicating compartments, packing means cooperating with said plates for resisting differences of pressure between said compartments, and means for moving said plates in time with each other so that the aperture in each plate will lie within said passage at a different time.

4. In a transfer passage for solids, movable apertured plates for dividing said passage into non-communicating compartments, packing means immediately surrounding said passage cooperating with said plates

for resisting differences of pressure between said compartments, and for scraping off material adhering to said plates, and means for moving said plates in time with each other 5 so that the aperture in each plate will lie within said passage at a different time.

5. In a transfer passage for solids, rotary apertured plates for dividing said passage into non-communicating compartments, 10 packing means cooperating with said plates for resisting differences of pressure between said compartments, and means independent of the axes of said rotary plates for rotating the plates, said means being coordinated so 15 that the aperture in each plate will lie within said passage at a different time.

6. In a transfer passage for solids, rotary apertured disks for dividing said passage into non-communicating compartments, 20 packing means cooperating with said plates for resisting differences of pressure between said compartments, and ring gears fixed to each disk, and a common driving means for said gears, said gears being timed so that the 25 aperture in each plate will communicate with said passage at a different time.

7. An apparatus for feeding material into a closed receptacle comprising a feed compartment, rotatable disks closing opposite 30 sides of said compartment, each disk having an aperture therein adapted to be registered with the compartment, a ring gear disposed on the periphery of each disk, a shaft, pinions on said shaft in mesh with said ring 35 gears, and means for turning said shaft.

8. An apparatus for feeding material into a closed receptacle comprising a feed compartment, rotatable disks closing opposite sides of said compartment, each disk having 40 an aperture therein adapted to be registered with the compartment, a ring gear disposed on the periphery of each disk, a shaft, pinions on said shaft in mesh with said ring gears, and means for turning said 45 shaft, and packing means surrounding said shaft adjacent said pinions.

9. A valve structure comprising a housing having a passage therethru, a pair of spaced disks rotatably journaled in the housing transverse to said passage, each disk having 50 an aperture therein adapted to be registered with said passage during its rotation, gear teeth arranged adjacent the periphery of each disk, a shaft having pinions in mesh with said gear teeth, and means for driving the shaft.

10. A valve structure comprising a housing having a passage therethru, a pair of spaced disks rotatably journaled in the housing transverse to said passage, each disk having 60 an aperture therein adapted to be registered with said passage, during its rotation, packing means surrounding the passage and between the housing and each

disk, and unitary means for rotating the 65 disks.

11. A valve structure comprising a housing having a passage therethru, a pair of spaced apertured disks rotatably journaled in the housing transverse to said passage, 70 said apertures being spaced at substantially 180° apart and adapted to be registered with said passage during rotation of the disks, packing means surrounding the passage and between the housing and each disk, and unitary means for rotating the disks. 75

12. In a valve structure, a pair of complementary hub blocks, and a rotary valve plate clamped between said blocks and restrained from rotation therebetween by frictional engagement with said blocks. 80

13. In a valve structure, a pair of complementary hub blocks, and a rotary valve plate clamped between said blocks and restrained from rotation therebetween by 85 frictional engagement with said blocks, a pin on which said hub blocks are journaled, and driving means removed from and independent of said pin and hub blocks for rotating said valve plate. 90

14. In a transfer passage for solids, rotary apertured plates for dividing said passage into noncommunicating compartments, and means independent of the axes of said rotary plates for rotating the plates, said 95 means being coordinated so that the aperture in each plate will be within said passage at a different time.

15. A valve structure comprising a housing having a passage therethru, a pair of spaced disks rotatably journaled in the housing transverse to said passage, each disk being of greater area than the cross sectional area of the passage and having an aperture therein adapted to be registered with said 100 passage during its rotation, plates on each side of each disk in frictional engagement with the surfaces thereof, and means for rotating said disks in time with each other so that one end of the passage is closed when 105 the other is open. 110

16. A valve structure comprising a housing having a passage therethru, a pair of spaced disks rotatably journaled in the housing transverse to said passage, each disk being of greater area than the cross sectional area of the passage and having an aperture therein adapted to be registered with said 115 passage during its rotation, plates on each side of each disk in frictional engagement with the surfaces thereof, and means independent of the axes of said disks for rotating the disks, said means being coordinated so that the aperture in each plate will lie within said passage at a different time. 120 125

In testimony whereof, I have hereunto set my hand.

EDGAR T. MEAKIN.
